UNITED STATES PATENT OFFICE

JOHN A. SPENCER, OF NEWTONVILLE, MASSACHUSETTS, ASSIGNOR TO GENERAL PLATE COMPANY, OF ATTLEBORO, MASSACHUSETTS, A CORPORATION OF MASSACHUSETTS

THERMOSTATIC HEATER

Application filed September 8, 1930. Serial No. 480,452.

This invention relates to thermostats, and with regard to certain more specific features, to thermostatic heaters.

Among the several objects of the invention 5 may be noted the provision of an improved form of thermostatic heaters adapted to reduce the lag which normally takes place between the time that a medium reaches a predetermined temperature and the time of operation of the thermostat; the provision of a device of the class described which has a more definite and effective thermostatic action under given conditions; the provision of a device of the class described which may be used 10 as an only heater or as an auxiliary heater, thus utilizing heat generated within the thermostat; the provision of a device of the class described in which the heat generated in the thermostat and utilized for heating also alters the operating characteristics of the 15 thermostat; and the provision of a device of the class described which is simple and compact, being adapted to be made portable, and fluid-proof. Other objects will be in part 20 obvious and in part pointed out hereinafter.

The invention accordingly comprises the elements and combinations of elements, features of construction, and arrangements of parts which will be exemplified in the structure hereinafter described, and the scope of the application of which will be indicated in 25 the following claims.

In the accompanying drawings, in which are illustrated several of various possible embodiments of the invention,

Fig. 1 is a longitudinal section taken 30 through a thermostatic heater embodying the invention;

Fig. 2 is a cross section taken on line 2—2 of Fig. 1;

Fig. 3 is an enlarged cross section of a switch;

Fig. 4 is a plan view of said switch shown 45 on the scale to which the switch is drawn in Fig. 3, or the view may be considered as a cross section on line 4—4 of Fig. 3;

Fig. 5 is a sectional detail showing an alternative mounting for certain thermostatic 50 elements;

Fig. 6 is a diagram illustrating applications of the invention; and,

Fig. 7 is a sectional detail of an alternative form.

Similar reference characters indicate corresponding parts throughout the several views of the drawings.

Referring now more particularly to Fig. 1, there is illustrated at numeral 1 a base to which is threaded, or otherwise fastened, an expansion element comprising in the present disclosure a Monel metal tube 3. At its outer end the expansion tube 3 is welded or otherwise fastened to a plug 5 from which extends a rod 7 composed, for example, of substantially non-expanding 42 per cent nickel steel. The rod 7 carries at its other end a fixed ferrule 9, between which and a shoulder 11 at the other end of the rod is carried a quartz tube 13 or the like. The quartz tube 13 is preferably in spaced relationship with respect to the rod 7 and, for optimum results, additional thermal insulating material 15, such as asbestos, is positioned between it and the rod, although this material may be dispensed with and air used as a thermal insulator.

From the above it will be seen that the movement of the inner rod 6 relative to the base 1 is substantially proportional to the elongation and contraction of the outer tube 3.

Around the quartz tube 13 is positioned, in the form of a double wire helix, an electrical heating element 19. The double wire helix 85 is referred to as providing one method for obtaining two line contacts for the heating element 19 at the inner end of the tube 13. The quartz tube 13 and the air space between the element 19 and the tube 3 constitute electrical 90 insulating means for the element 19 with regard to the rod 7 and the tube 3, respectively. Thus the heating element 19 may be conveniently connected in series in a circuit 21, said circuit being adapted to be opened and closed 95 by means of a buckling, over-centering switch 23 located in a recess 25 of the base 1.

The switch 23 is shown more particularly in Fig. 3 where it is shown as comprising a switch plate 27 held to the base 1. This plate 100

- 27 carries in insulated relationship a series of the disc to spring suddenly to the line position shown in Fig. 3 and again close the circuit. 70
- 5 27 carries in insulated relationship a series of the disc to spring suddenly to the line position shown in Fig. 3 and again close the circuit. 70
- 5 27 carries in insulated relationship a series of the disc to spring suddenly to the line position shown in Fig. 3 and again close the circuit. 70
- 5 27 carries in insulated relationship a series of the disc to spring suddenly to the line position shown in Fig. 3 and again close the circuit. 70
- 5 27 carries in insulated relationship a series of the disc to spring suddenly to the line position shown in Fig. 3 and again close the circuit. 70
- 10 The cuffed disc 35 in its nature inherently tends to maintain the full line position shown in Fig. 3, having been formed to the contour there shown. However, if by external force, it is caused to assume a reverse curvature, it 75
- 15 will maintain the reverse curved position. This is characteristic of resilient, dished or cupped articles. 80
- 20 When in its solid-line position, the disc 35, as will be seen later, is adapted to hold the terminal engaging elements 33 in engagement with the line terminals 29 to bridge the same; and when in its reverse curved position, to hold them out of engagement. Three 85
- 25 elements 33 are used in order to obtain a series of breaks. The dotted lines in Fig. 3 indicate rotated positions of certain parts for purposes of clearly demonstrating mechanical action. 90
- 30 Switch action is accomplished by loosely mounting the disc 35 at a central opening 37 between spaced collar 39 of a reciprocable switch control pin 41. Three studs 43 screwed to the switch plate 27 serve to guide the disc 35, the heads 42 of said studs 43 providing a reacting fulcrum for purposes to be 95
- 35 made clear. 100
- 40 The switch pin 41 is reciprocably mounted within a bushing 47 screwed and locked to the switch plate 27 and having a slotted portion 49 with which co-operates key 51 in the pin 41, so that reciprocation of the pin 51 in the bushing 47 is permitted without rotation of said pin. At its lower end the pin 41 carries a head 53 against which reacts a compression spring 55. 105
- 45 Permitting full or partial compressive action of the spring 55 on the head 53, causes the pin 41 to be pushed down, thereby pushing down the disc 35 so that the terminal engaging elements 33 incipiently increase contact pressure (circuit 21 closed) and then, as a reaction is set up at the edge of the disc to the primary action of the center thereof caused by the pin 41, the disc snaps into reverse curved position, thereby opening the circuit. Continued downward action of the pin 41 is limited by co-operation of one of the shoulders 39 with the bushing 47, thus preventing a subsequent closure of the switch. 115
- 50 If the head 53 of the pin 41 is pushed toward the switch against the reaction of the spring 55, the disc 35 is pushed outwardly so that it touches the heads of the studs 43. 120
- 55 This action, after suitable movement, causes 125

by, as the critical temperature is reached, thus rapidly increasing the relative displacements between the elements of the thermostatic linkage. This phenomenon is true regardless of the temperature coefficients of expansion of the rod and the tube, which may differ as in the exemplary case of Monel and nickel steel recited, or which may be the same, as when the rod and tube are formed of the same metal. The greater difference in tube and rod temperatures than medium and rod temperatures ensures more definite and prompt thermostatic action for a given temperature of medium, especially when their temperature coefficients of expansion are unequal.

Another point to be noted is that after the thermostat opens the switch, the tube temperature quickly drops back to that of the medium, thus shortening the delay until reclosing of the switch and ensuring less drop in the temperature of the medium before re-closing. The difference between the temperature of the tube and the medium upon heating may in fact be made great enough so that the lower limit temperature of the tube and rod required for reclosing is reached before the temperature of the medium has dropped any substantial amount.

It will be clear from the above that the invention is operative even though the tube 3 and rod 7 be composed of the same material, the relative movement depending upon their temperature difference. Furthermore, a negative, finite operating temperature differential may be obtained, more readily if the coefficient of expansion of the inner rod 7 be higher than that of the tube 3. The operating temperature differential is defined as the temperature difference that must exist between the thermostat and medium before change of position occurs. Ordinarily, this differential is expressed as a positive value, as representing, say in the cooling phase, the number of degrees the medium must be cooler than the thermostat before the heater is energized to change the system over to the heating phase. A differential of zero is achieved when the change-over occurs when the thermostat and medium are at exactly the same temperature. A negative, finite differential, as the terms are herein used, is defined as a differential such that the change-over might occur while the thermostat, in the cooling phase, is even cooler than the medium.

When the rod 7 is substantially non-expansive and is shielded from the heating effect of the coil 19, the desired effect is enhanced, because the necessary, though exceedingly small changes in length of this rod, due to temperature changes, are rendered smaller.

The following is pointed out in order to clarify the invention:

Were the heater element 19 not used, but only the heater 67, the thermostat then

being only an ordinary rod-and-tube type thermostat, all temperature difference would be on a gradient descending from the medium to the tube 3, due to transferring heat from the medium 69 to the tube 3. Thus there would be a lag in the operation of the switch 23 in comparison with the medium attaining a predetermined temperature.

With the heater 19 operative, the temperature difference grades from the tube 3 to the medium 69 and this results in the switch actually operating at a temperature of the tube 3 which is higher than that of the medium 69. This also permits the thermostatic linkage to operate between wider limits, which is advantageous in the case of a thermostat, providing more powerful, definite and positive action.

It is to be understood that all of the heating of the medium 69 may be accomplished by means of the heater element 19, if desired, and for this purpose a disconnection is made at the point 71 (Fig. 6) and the heater 67 removed. Current is then supplied directly across the terminals of the thermostat. In many cases this is advantageous from the viewpoint of simplicity. It also ensures that the thermostat is operating in the circuit when the heater is operating, thus making a safe structure for heating purposes.

In Fig. 5 is shown an alternative method for fastening the rod 7 within the tube 3 so that the rod is more effectively insulated therefrom. In this modification a thermal insulating plug 73 composed preferably of porcelain, is placed at the end of the tube 3. The plug 73 supports the rod 7 and a suitable cap 75 is applied.

A modified form of the invention is shown in Fig. 7 which includes the outer expansive tube 3 and inner expansive rod 7. A small heating unit 2 is found in close juxtaposition with the top 3 but electrically insulated therefrom by a thin layer of heat-transmitting material 4. This material 4 may comprise, for instance, a thin sheet of mica. The thermal contact of the heated tube with the rod 7 is poor. The air space between the unit 2 and the rod 7 now assumes the relative rôle of a heat insulator, because its heat conductance is lower than that of the mica layer 4. Both mica and air space, of course, are electrical insulators for the unit 2.

If this alternative form is installed in a boiler, preferably near the bottom, as long as there is water surrounding the tube there will be little difference in temperature between tube and rod, and the device will hence not operate, no matter what the temperature of the boiler may be. If, however, there be no water present the difference in temperature will be large. This, therefore, could be used as a low water alarm.

It is to be noted that this form presents

conditions somewhat different from those above referred to. It is true difference in temperature between tube and rod depends upon the water temperature to some extent, 5 and in fact this could be used to operate the thermostat as above discussed. The difference in temperature in the entire absence of water will, however, be much greater than the above. Therefore, for the low water

10 alarm the thermostat can be set to operate only at a relatively large temperature difference as compared with the setting when the same device is used for controlling the water temperature.

15 It is to be understood that the invention herein disclosed may be used in connection with various mechanical and other devices, the tube 3 being suitably mounted so that it may expand and contract while in contact with the medium or material, the temperature of which is to be controlled. The fluid-tight cover 22 for the switch 23 and connected elements is applied over the base 20 1 where the device is to be totally immersed 25 (Fig. 1).

It will be seen that the switch herein is of the snap-acting type, externally operated. It is to be understood that other snap-acting switches may be used, such as over-centering toggle switches or the like.

30 This invention is novel in providing a thermostat and a heater such that the heater heats the ambient medium and is in close proximity to one thermostatic element, this fact in itself 35 accounting for many advantages, as well as the fact that the fluid is heated by way of one element.

In view of the above, it will be seen that the several objects of the invention are 40 achieved and other advantageous results attained.

45 As many changes could be made in carrying out the above constructions without departing from the scope of the invention, it is intended that all matter contained in the above description or shown in the accompanying drawings shall be interpreted as illustrative and not in a limiting sense.

50 I claim:

50 1. A thermostatic heater comprising two concentric elements, said elements comprising a rod and a tube enclosing the rod, said elements being joined at one end, the other ends 55 of said elements being free for relative movement, an electrical heating means between said elements, electrical insulating means between said heating means and one of said elements constituting a relatively good conductor of heat, and additional electrical insulating means between said heating means and the other of said elements constituting effective heat insulating means as well.

60 2. A thermostatic heater comprising a thermally responsive tube and a rod surrounded 65 thereby, said tube and said rod being joined

at one end, the other ends of said tube and said rod being free for relative movement, an electrical heating element between said rod and said tube, electrical insulating means between said element and said tube constituting a relatively good conductor of heat, and electrical insulating means between said element and said rod constituting effective heat insulating means as well.

70 3. A thermostatic heater comprising a thermally responsive tube and a rod surrounded thereby, said tube and said rod being joined at one end, the other ends of said tube and said rod being free for relative movement, an electrical heating element between said rod and said tube, an air space between said element and said tube electrically insulating said element from said tube but permitting relatively free flow of heat from said element to said tube, and a quartz tube electrically insulating said element from said rod, and in addition presenting an effective heat insulation between said element and said rod.

75 4. In combination, a thermostatic heater 80 immersed in a body of medium, the temperature of which it is desired to control, said thermostat comprising a thermally responsive tube and a rod surrounded thereby, 85 said tube and said rod being joined at one end, the other ends of said tube and said rod being free for relative movement, an electric switch operated by the 90 relative movement of said free ends, an electrical heating element between said rod and said tube, said heating element being connected in series with said electric switch, electrical insulating means between said element and said tube constituting a relatively good 95 conduction of heat, and electrical insulating means between said element and said rod constituting effective heat insulating means as well.

100 In testimony whereof, I have signed my name to this specification this 7th day of 105 August, 1930.

JOHN A. SPENCER.
